UNITED STATES PATENT OFFICE.

FRIEDRICH MORITZ WOLF, OF GLAUCHAU, SAXONY, ASSIGNOR
TO F. E. OBERMULLER.

IMPROVEMENT IN LOOMS.

Specification forming part of Letters Patent No. 44,271, dated September 13, 1861.

To all whom it may concern:

Be it known that I, FRIEDRICH MORITZ WOLF, of Glauchau, in the Kingdom of Saxony, have invented a new and useful Improvement in Weaving-Machines; and I do hereby declare that the following is a full, clear, and exact description thereof, which will enable those skilled in the art to make and use the same, reference being had to the accompanying drawings, forming a part of this specification, in which—

Figure 1 represents a sectional side elevation of my invention, showing that side of the machine turned toward the operative when at work. Fig. 2 is a plan or top view of the same. Fig. 3 is a longitudinal vertical section of the same, the line $x-x$, Fig. 2, indicating the plane of section. Fig. 4 is an end view of the same, partly in section. Figs. 5, 6, and 7 are detached elevations of the perpendicular wires and needles. Fig. 8 is a detached sectional view of the endless apron with blocks to govern the position of the needles.

Similar letters of reference indicate corresponding parts.

The object of this invention is an attachment to looms calculated to obviate the difficulties attending treadle-machines or draw-looms with a large number of heddle-shafts, and to supersede the Jacquard machine, and which is so arranged that for the production of a certain pattern or design no cards, or only a very limited number of the same, are required, and at the same time it admits of an innumerable variety of changes in the pattern or design without much loss of time or expense, and each portion of the pattern can be formed or combined in any desirable manner, also, without much loss of time. Treadle-machines of the ordinary construction up to this time could not be worked conveniently with more than sixteen heddle shafts, because it is very difficult with a large number of shafts to produce a clean shed, and a larger number than that above stated of ordinary shafts occupies too much space in depth, and the practical operation of such machines is difficult and very tiresome. In all cases, therefore, where a larger number of shafts would be requisite the Jacquard machine has been employed, the preparation of which requires much time

and expense. With both these machines, however, with the shaft-machine, and with the Jacquard machine it is necessary to prepare new cards for each new pattern. Furthermore both machines have the disadvantage, that if a certain combination with a certain pattern or part of a pattern does not give a good effect, new cards have to be prepared for the whole, or the combination must be corrected on the cards at a great loss of time. These disadvantages are obviated by my invention, the construction of which is described in the following:

A A are two wooden rails, which support my machine, and to which the cast-iron frame B B is firmly secured. The arms C of the frame B form the bearings for the fulcrum-pin E' of the lever E, which serves to impart to the griff-frame F the requisite reciprocating motion by means of a treadle and counter-weight, or by two treadles, in which case one treadle forms the substitute for the counter-weight. The griff-frame F, with the two knives F' and F'', serves to raise the perpendicular wires or skewers G G, which are arranged in two rows on the harness-board H. This harness-board is hinged, being made to swing on a fulcrum-pin, H, the bearings of which are in two arms, projecting from one of the foot-rails A, generally on that side facing the operator, whereas the opposite end of said harness-board connects with a rod, K, which may be double, and which is suspended from one end of the working-beam J, the opposite end of which connects by a rod, K', with the griff frame F. The inner end of the lever E connects by links L with the bell-crank levers M, which have their fulcrum on pivots N. Counter-weights M', of suitable size, are suspended from the lower arms of the bell-crank, which also connect with the links L, and the other perpendicular arms of said bell-crank levers form the bearings for the large cylinder O. The construction of this cylinder is similar to that in ordinary weaving-machines, but it is larger in proportion and provided with larger holes than the ordinary cylinder. It is provided with a lantern, P, of the usual construction, and this lantern is subjected to the pressure of the foot Q, which is held down by a spring, R, and guided

in a suitable bracket attached to the perpendicular arm of the elbow-lever M. Two pawls, S S', arranged in the usual manner, one above and the other below the lantern P, serve to impart to the cylinder the desired rotary motion in either direction. The small cylinder b has its bearings in levers a, which have their fulcra on pivots a', projecting from the outer surfaces of the frame B, and by those arms said small cylinder is moved up and down in slots b' in the side pieces of the frame. The small cylinder is not perforated with holes, but it is furnished with lanterns b*, similar to the lantern P of the large cylinder, and held in position by a foot, b'', in the ordinary manner, as above stated. The object of the small cylinder is to impart motion to the endless chain c, the sections of which are arranged to carry the movable blocks c*, which govern the position of the perpendicular wires or palisades c, and through them that of the needles and skewers. Said skewers are situated in close proximity to the slotted needle-plate d*, one opposite each slot in said plate, and they are furnished with springs e, which bear against a cross-bar, d, which, together with the lower cross-bar, d', form the guides for said palisades. The springs e have a tendency to press the palisades down, and by their action the lower ends of the same are always held in contact with the surface of the endless apron, or that of the blocks secured to the same. The needle-plate d* is made of sheet-iron or other suitable material, and it is provided with slots to allow the needles f to rise and fall. Said needles are held by the palisades in two horizontal rows, one above the other, and through the eyes of said needles pass the skewers G, which are raised by the action of the knives F' F'' in the griff-frame. The needle or spring-box g is made of wood or other suitable material in the usual manner. The levers a are exposed to the action of springs h, or, instead of these springs, a weight may be applied so that the small cylinder is forced up, and said levers are provided with slots a', which form the bearings for a transverse rod, i*, on which the hooks rotate freely in either direction. These hooks rise in a vertical direction above the knife F' of the griff-frame, and their lower ends are bent at right angles and connected by a weighted cross-bar, i, whereby they (the hooks) are drawn off from the knife. The object of these hooks is to cause the small cylinder to descend, and thereby compel the same to turn, and this object is effected either by hand, by pulling the cord k', which is connected to one of the hooks, and which is used if the picture is to be changed after more than four shoots, or the hooks may be moved automatically by the action of the large cylinder on the rod l, which is attached to the lower end of a double-armed lever, l*, the upper end of which connects by a suitable rod, l', with one of the hooks. The rod l extends

from the lever l* back to the large cylinder, and its point drops into suitable holes in the sides of said cylinder. Usually all these sides will be provided with such holes, and suitable slides will be provided to shut off either one of the holes, and as the cylinder rotates the point of the rod l will come in contact with said slide or slides. The large cylinder makes one-quarter revolution for each stroke of the lever E, and whenever it has been rotated far enough so as to bring that side in which the hole has been shut off in contact with the point of the rod l, said rod is pushed back, and by the action of the lever l* the hooks are pressed forward and caused to catch over the knife F'. Whenever this takes place the small cylinder is depressed and turned, and the pattern is changed. The turning of the small cylinder is effected by the pawls o o catching over the studs in the lanterns b* in the usual manner. If desired, the small cylinder may be placed above the needles f, and so arranged with two pawls that it can be turned backward and forward. The chain c, which works on the small cylinder, is composed of a series of plates which are so arranged that they are capable of holding each a number of blocks c*, made of four different heights, and arranged according to the pattern to be produced. (See Fig. 8.) By those blocks the palisades c are raised to different heights and the needles f are made to arrange themselves in four different positions, according to the pattern, so as to enable them to drop into the requisite holes in the sides of the large cylinder. The harness or shaft arrangement is effected in the usual manner, and requires no further explanation.

For power-looms the construction of my machine is substantially the same as above described, but the whole must be made stronger, and the axle of the large cylinder O is made partially square to carry an endless chain, the number of plates of which corresponds to the number of shoots required for the pattern to be produced, and which serves to cause the small cylinder b to turn automatically as required by the design or pattern by its action on the rod l, which in that case is placed opposite to this additional endless chain instead of to the large cylinder.

The operation of this machine and the various effects produced thereby are as follows: If the main lever E is depressed or pulled down by the action of the treadle, the griff-frame F rises. By the action of the rod K', which connects the griff-frame with the working-beam J, one arm of this beam is raised, and the opposite arm, together with the harness-board H, is depressed. The skewers resting on said board sink down with it, and thereby a regular shed is produced, and the fabric becomes more even and uniform than by the ordinary loom. Simultaneously with the rising of the griff-frame by the action of the lever E the lower arm of the elbow-lever

M is drawn up, whereby the large cylinder O is caused to swing in the direction of the arrow marked near it in Fig. 1, and at the same time by the action of the pawls S said cylinder is turned so as to bring on another card or perforated side opposite the needles f and the rod l and other warp threads or lashes are raised or depressed. If the hooks i i are drawn over the knife F', they rise simultaneously with the griff-frame and the small cylinder b is depressed and caused to turn on its axis. By this motion a new set of blocks is brought to bear against the lower ends of the palisades c, and by the change in the position of said palisades the needles f are raised and depressed in the slotted needle-plate. By this varying position of the needles different combinations in the pattern can be produced without changing the cards, which rotate with the large cylinder, and which are provided with a different combination of holes for each row of holes in the cylinder, the needles being raised or depressed to the proper position by the blocks c* so that they are enabled to meet the row corresponding to the combination to be produced. Whenever the pattern is to be changed, the hooks i i are drawn over the knife F' either by the action of the large cylinder on the rod l or by hand, and the small cylinder is turned. With the jacquard, and also with the treadle or draw-loom each needle operates separately for itself; but in my machine the blocks c* according to their width raise each one or two palisades and consequently two or four needles.

while at the same time each needle is operated upon independently of the others by the action of the cards on the large cylinder.

I claim as new and desire to secure by Letters Patent—

1. The movable blocks c*, applied in combination with the large cylinder O, substantially in the manner and for the purpose herein shown and described.

2. The arrangement of the lever E, working-beam J, hinged harness-board H, elbow-lever M, and arms a, in combination with each other and with the cylinders O b and griff-frame F, substantially as herein specified, so that simultaneously with the raising of the griff-frame and depressing of the harness-board the cylinders O and b are moved and turned.

3. The slotted needle-plate d* and palisades c, in combination with the needles f and skewers G, arranged and operating in the manner and for the purpose substantially as herein set forth.

4. The endless chain c', composed of a series of plates, each capable of receiving and holding a quantity of adjustable blocks c*, constructed and operating substantially as herein specified, so that by a simple change in the blocks the pattern or design can be changed at pleasure.

FRIEDRICH MORITZ WOLF.
